United States Patent [19]

Duftschmid

[11] Patent Number: Des. 311,871

[45] Date of Patent: ** Nov. 6, 1990

[54] RADIATION MEASURING DEVICE OR
SIMILAR ARTICLE

[75] Inventor: Klaus Duftschmid,
Gumpoldskirchen, Austria

[73] Assignee: Oesterreichisches Forschungszentrum
Seibersdorf Ges.m.b.H., Seibersdorf,
Austria

[**] Term: 14 Years

[21] Appl. No.: 114,373

[22] Filed: Oct. 29, 1987

[30] Foreign Application Priority Data

May 14, 1987 [AT] Austria 542764

[52] U.S. Cl. D10/47

[58] Field of Search D10/47, 96, 97;
250/336.1, 475.2, 472.1, 374, 482.1; 324/95

[57] CLAIM

The ornamental design for radiation measuring device
or similar article, as shown and described.

DESCRIPTION

FIG. 1 is a top, front, and right side perspective view of
a radiation measuring device or similar article showing
my new design;

FIG. 2 is a top plan view;

FIG. 3 is a bottom plan view;

FIG. 4 is a left side elevational view;

FIG. 5 is a right side elevational view;

FIG. 6 is a rear elevational view; and

FIG. 7 is a front elevational view thereof.

FIG. 1.

FIG 2

FIG 3

FIG. 4.

FIG. 5.

FIG. 6.

FIG. 7.
